UNITED STATES PATENT OFFICE.

ARTHUR TREVOR DAWSON, OF WESTMINSTER, LONDON, AND JAMES HORNE, OF BARROW-IN-FURNESS, ENGLAND, ASSIGNORS TO VICKERS LIMITED, OF WESTMINSTER, LONDON, ENGLAND.

AMMUNITION HOISTING AND LOADING APPARATUS.

1,289,694.

Specification of Letters Patent.

Patented Dec. 31, 1918.

Application filed June 16, 1915. Serial No. 34,547.

To all whom it may concern:

Be it known that we, Sir ARTHUR TREVOR DAWSON, knight, and JAMES HORNE, both subjects of the King of Great Britain, residing, respectively, at Vickers House, Broad- 5 way, Westminster, in the county of London, England, and Naval Construction Works, Barrow-in-Furness, in the county of Lancaster, England, have invented certain new and 10 useful Improvements in or Relating to Am- munition Hoisting and Loading Apparatus, of which the following is a specification.

This invention relates to ammunition hoisting and loading apparatus of the kind 15 in which the gun loading cage is provided with a movable support for the powder charge this support being controlled by the rammer in such a manner that it is permitted to move step by step so that it assumes the 20 required positions for enabling the elements of the powder charge to be discharged through an opening in the cage on to the projectile tray for ramming into the gun.

According to this invention, the powder 25 charge elements are retained in place in the cage partly by shelves or trays constituting the powder charge support and partly by the body of the cage through the opening of which the powder charge elements pass 30 in succession to the projectile tray by a step by step movement imparted to the said support. Two such shelves or trays for the quarter powder charges may be employed, these shelves or trays being adapted to swing simultaneously in a plane transverse to the axis of the gun; means are provided whereby 35 the rammer upon its return stroke after ramming the projectile, shifts a device into a position to liberate the said shelves or trays 40 and by their movement to discharge the first two quarter charges laterally on to the projectile tray, whereupon the device brings the shelves or trays to rest and then after the ramming of these charges and on the re- 45 turn stroke of the rammer to again liberate the shelves or trays and bring them to rest after discharging the second two quarter charges laterally on to the projectile tray. This device may comprise a movable stop 50 connected by suitable mechanism with a

member adapted to be displaced by the rammer head when it approaches its fully withdrawn position, this stop being capable of assuming three positions in succession. Moving with the support is a plate or the 55 like having three stepped projections or shoulders representing three different positions of the support viz: "fully closed;" "lower shelf discharged" and "upper shelf discharged," the movable stop engaging with 60 these shoulders in succession when it is actuated by the rammer head. Manually operated means may be provided for placing the said stop in the said positions successively when it is desired to effect the dis- 65 charging operations by hand.

In order that the said invention may be clearly understood and readily carried into effect, we will describe the same more fully with reference to the accompanying draw- 70 ings, in which:

Figures 1 and 2 are respectively a rear elevation and a partial side elevation of a gun loading cage provided with a constructional form of our improvements. 75

Figs. 3 and 4 are diagrammatic rear elevations showing the position assumed by the powder charge support and its associated parts when the rammer reaches its fully withdrawn position after ramming the projectile and after ramming the first two powder charges respectively, and 80

Figs. 5 and 6 are diagrammatic side elevations showing the member which is displaced by the rammer head and is connected 85 to the movable stop, in positions corresponding to those illustrated by Figs. 3 and 4.

A is the gun loading cage and A' is the opening therein through which the powder charge elements pass on to the projectile tray 90 A'. B is the rammer-head. C represents the aforesaid powder charge support and c c' represent its shelves or trays. D represents the aforesaid movable stop and D' the member connected thereto and adapted to be 95 displaced by the rammer head. E represents the aforesaid plate moving with the support and e, e', e² represent its stepped projections or shoulders.

In the example shown the support C is 100

rígidly mounted on a spindle C' between the end plates of the gun loading cage A. The aforesaid stepped plate E is attached to the rear end of the said spindle and is formed with a groove E' having the stepped shoulders e, e', e² for coöperating with a roller D constituting the aforesaid movable stop and carried by a pivoted arm d. This arm is connected by a link d' to a spindle 10 d² projecting laterally from the lower part of the cage and carrying the aforesaid member D' which is in the form of an arm having a shoulder D² with the front surface of which a projection F on a two armed lever 15 F', F² coöperates; these arms are normally disposed in front of the rammer head B as shown by Fig. 2. When the rammer performs its projectile ramming stroke its head over-rides the arm F' but engages with it on the return stroke (Fig. 5) and thereby 20 displaces the roller D into a position shown by Fig. 3 which is such that the powder charge support is free to move about its pivot under the influence of gravity until 25 arrested by the coöperation of the roller D with the shoulder e' (see Fig. 3). The first two quarter charges will then have been deposited on the projectile tray by the movement of the tray or shelf c. When the rammer commences its outward stroke to ram 30 these charges, the rammer head will over-ride the arm F² and on the return stroke will engage with it to displace the roller D into the position shown by Fig. 4 in order 35 to again free the support which moves to discharge the remaining two quarter charges, whereupon the support is again brought to rest as shown in Fig. 4 by the coöperation of the roller D with the shoulder e². When 40 the cage is lowered a suitable cam on the loading arm engages with a roller or projection E^x on the aforesaid stepped plate E to restore the support to its fully closed position, a spring d^x which operates upon the 45 arm d causing the roller D to move to its original position shown by Figs. 1 and 2.

The arm d and its roller D may be displaced manually by means of a hand lever G movable within certain limits determined 50 by the coöperation of a projection g^x on the hand lever with fixed stops g g'. The hand lever is provided with a spring catch G' and the arm d is formed with three notches. Thus when it is desired to displace the support C by hand the hand lever is moved in 55 an anti-clockwise direction (the catch G' being at this time not in engagement with the right hand notch in the arm d) until the projection g^x bears against the stop g'. The projection g^x then engages with the second or 60 middle notch in the arm d so that by moving the hand lever G in a clockwise direction until the projection g^x comes against the stop g the roller D will have been brought 65 into the position shown by Fig. 3 so that

the support C can move one step to discharge the first two quarter charges; a similar operation takes place in moving the roller D into the position shown by Fig. 4. The catch G' is normally held by its spring 70 out of engagement with the notches so that the hand lever G is unconnected with the arm d when the latter is being moved automatically by the rammer head as aforesaid.

The plate E in the example shown carries 75 a spring plunger E² which during the movements of the support C coöperates with cam surfaces A², A³ on the cage and serves as a brake for the support. The degree of compression of the spring of this plunger may 80 be adjusted so that the braking action can be varied as desired.

What we claim and desire to secure by Letters Patent of the United States is:—

1. In ammunition hoisting apparatus, the 85 combination with the ammunition cage and a movable powder charge support carried thereby, of shelves forming part of said support, the powder charge elements being retained in place partly by said shelves and partly by the body of said cage and means for imparting a step by step movement to said support to enable the powder charge elements to escape from the cage through 90 an opening therein. 95

2. In ammunition hoisting apparatus, the combination with the ammunition cage and a movable powder charge support carried thereby, of shelves forming part of said support, the powder charge elements being 100 retained in place partly by said shelves and partly by the body of said cage, and means for enabling said support to move step by step to permit the powder charge elements 105 to escape from the cage through an opening therein.

3. In ammunition hoisting apparatus, the combination with the ammunition cage and a movable powder charge support carried thereby, of shelves forming part of said support, the powder charge elements being 110 retained in place partly by said shelves and partly by the body of said cage, and means for enabling said support to move step by step to permit the powder charge elements 115 to escape from the cage through a lateral opening therein.

4. In ammunition hoisting apparatus, the combination with the ammunition cage, of a swinging powder charge support carried 120 thereby, shelves forming part of said support, the powder charge elements being retained in place partly by said shelves and partly by a curved portion of said cage and means for imparting a step by step swinging movement to said support to enable the powder charge elements to escape from the cage through an opening therein. 125

5. In ammunition hoisting apparatus, the combination with the ammunition cage of 103

a swinging powder charge support carried thereby, shelves forming part of said support, the powder charge elements being retained in place partly by said shelves and

5 partly by a curved portion of said cage, and means for enabling said support to move step by step to permit the powder charge elements to escape from the cage through an opening therein.

10 6. In ammunition hoisting apparatus, the combination with the ammunition cage, the projectile tray carried thereby and the movable powder charge support carried by said cage, of shelves forming part of said support,

15 the powder charge elements being retained in place partly by said shelves and partly by the body of said cage, and means for imparting a step by step movement to said support to enable the powder charge

20 elements to pass in succession to the projectile tray through an opening in the cage.

7. In ammunition hoisting apparatus, the combination with the ammunition cage, the projectile tray carried thereby and the movable powder charge support carried by said cage, of shelves forming part of said support, the powder charge elements being retained in place partly by said shelves and partly by the body of said cage, and means

30 for alternately liberating said support and bringing it to rest to enable the powder charge elements to pass to the projectile tray through an opening in the cage.

8. In ammunition hoisting apparatus, the combination with the ammunition cage, and the projectile tray carried thereby, of a swinging powder charge support carried by said cage, shelves forming part of said support, the powder charge elements being retained in place partly by said shelves and partly by the body of said cage, and means for imparting a step by step swinging movement to said support, to enable the powder charge elements to pass in succession to the projectile tray through an opening in the cage.

9. In ammunition hoisting apparatus, the combination with the ammunition cage and the projectile tray carried thereby, of a swinging powder charge support carried by said cage, shelves forming part of said support, the powder charge elements being retained in place partly by said shelves and partly by a curved portion of said cage, and means for alternately liberating said support and bringing it to rest to enable the powder charge elements to pass to the projectile tray through an opening in the cage.

10. In ammunition hoisting apparatus, the combination with the ammunition cage, the projectile tray carried thereby and the movable powder charge support carried by said cage, of shelves forming part of said support, the powder charge elements being retained in place partly by said shelves and

partly by the body of said cage, and means for imparting a step by step movement to said support to enable the powder charge elements to pass by the action of gravity to the projectile tray through an opening in the 70 cage.

11. In ammunition hoisting apparatus, the combination with the ammunition cage, the projectile tray carried thereby, and a gravity controlled movable powder charge support 75 carried by said cage, of shelves forming part of said support, the powder charge elements being retained in position partly by said shelves and partly by the body of said cage, stepped projections carried by said support, 80 and a movable stop carried by the cage and adapted to coöperate with said stepped projections to permit the support to move step by step and thereby enable the powder charge elements to pass in succession to the 85 projectile tray through an opening in the said cage.

12. In ammunition hoisting apparatus, the combination with the ammunition cage, and the projectile tray carried thereby, of a gravity controlled swinging powder charge support carried by said cage, shelves forming part of said support, the powder charge elements being retained in position partly by said shelves and partly by a curved portion 90 of said cage, stepped projections carried by said support and a movable stop carried by the cage and adapted to coöperate with said stepped projections to permit the support to swing step by step and thereby enable the 100 powder charge elements to pass in succession to the projectile tray through an opening in the said cage.

13. In ammunition hoisting apparatus, the combination with the ammunition cage, 105 the projectile tray carried thereby, the gravity controlled movable powder charge support carried by said cage and the rammer for ramming the projectile and the powder charge elements into the gun, of shelves 110 forming part of said support, the powder charge elements being retained in position partly by said shelves and partly by the body of said cage, stepped projections carried by said support, a movable stop carried by 115 the cage and adapted to coöperate with said stepped projections to permit the support to move step by step and thereby enable the powder charge elements to pass in succession to the projectile tray through an opening 120 in the said cage, and means operated by the rammer for moving said stop into its various positions.

14. In ammunition hoisting apparatus the combination with the ammunition cage, the projectile tray carried thereby, and the gravity controlled movable powder charge support carried by said cage, of shelves forming part of said support, the powder charge elements being retained in position partly by 130

said shelves and partly by the body of said cage, stepped projections, carried by said support, a movable stop carried by the cage and adapted to coöperate with said stepped projections to permit the support to move step by step and thereby enable the powder charge elements to pass in succession to the projec-

tile tray through an opening in the said cage, and hand operated means for moving said stop into its various positions. 10

In testimony whereof we affix our signatures.

ARTHUR TREVOR DAWSON.
JAMES HORNE.
